UNITED STATES PATENT OFFICE

FREDERICK T. SNYDER, OF NEW CANAAN, CONNECTICUT

PRODUCTION OF HYDROGEN

Application filed December 16, 1925, Serial No. 75,795, and in Canada March 12, 1925.

This invention relates broadly to the art of hydrogenating hydrocarbons and carbohydrates, and more particularly to a method or process of producing, at low cost and in large quantities, hydrogen or gas mixtures containing a large amount of free hydrogen and suitable for hydrogenation processes.

Generally speaking, the invention resides in cracking natural gas or gas distilled from coal, oil or other suitable material, by passing the same in contact with hot refractory material in closed chambers with exclusion of air, and burning with air in the chambers the carbon deposited from the cracking operation, to reheat the refractory material. These operations are performed alternately.

It is, of course, well known that methane, the chief constituent of natural gas, can be dissociated into hydrogen and carbon by heating the gas to a sufficiently high temperature with exclusion of air. Other gases or hydrocarbon vapors with high hydrogen content may be cracked in the same way, yielding hydrogen, carbon and residual gases according to the nature of the original gas or vapor. The carbon deposited when natural gas is cracked is sufficient in amount, when burned with air, to furnish more heat than necessary to effect the cracking. The excess heat offsets loss by radiation and may be used to heat the produced high hydrogen gas, to generate steam, or for other purposes. For the economic accomplishment of these results, it is essential that the gas and air should pass through the cracking chamber in opposite directions. Under these conditions the incoming cold gas and cold air operate to sweep the heat toward the centre of the chamber and produce a hot zone at the centre. Preferably the interior of the cracking chamber is a brickwork checker.

To facilitate comprehension of the invention, one manner of putting the same into practice will be described, reference being made to the accompanying diagrammatic drawing illustrating one suitable form of apparatus.

Referring more particularly to the drawing which diagrammatically represents a vertical sectional view of suitable apparatus,

11 designates a steel shell, which serves to prevent leaks. This shell has a refractory heat insulating lining 12 and is in large part filled with a refractory checkerwork 13. The cold gas to be cracked enters through a pipe 14 which may be opened and closed by a valve 15. The hot cracked gas leaves through a pipe 16 controlled by a valve 17. The air for the burning of the deposited carbon enters through a pipe 18 having a valve 19, and the products of the combustion of the carbon leaves through the pipe 20 in which is a valve 21. The air is supplied by a blower 18a.

Carbon having been deposited on the refractories in the centre zone of the checkerwork 13, the hot and cold gas valves 15 and 17 are closed and the air valve 19 and the stack valve 21 are opened. The passage of the hot gas on the previous cycle having heated the checkerwork at the lower end 22, the incoming air is heated and at the same time this end of the checkerwork is cooled. The heated air burns the deposited carbon causing a high temperature in the centre zone. This heat is absorbed by the checkerwork and part of it is carried out of the centre zone by the products of the combustion which have also risen to a high temperature from the combustion. The upper end 23 of the checkerwork is cool as the result of the incoming cold gas sweeping over it in the preceding cycle. The hot products of the combustion leaving the centre zone give up most of their heat to this cooled brickwork in the upper zone and go out through the pipe 20 to the stack at a comparatively low temperature.

When the combustion of the deposited carbon is complete, the valves 19 and 21 controlling the air and stack pipes are closed and the gas valves 15 and 17 are opened. The incoming cold gas is heated gradually by the heat left in the upper zone 23 of the checkerwork by the outgoing products of the combustion. When this heated gas reaches the centre zone of the checkerwork 13, the gas is carried to a temperature so high that all of the hydrocarbon compounds, such as methane and ethane, are decomposed. This decomposition is sub-

stantially complete at 1500° F., but in practice the checkerwork in the centre zone is heated to 1800° F. to shorten the time of the decomposition. As the cracking is largely brought about by the contact of the gas with the hot checkerwork, the carbon freed as the result of the cracking is in contact with the checkerwork and adheres to it as a solid deposit. This adherence is facilitated by the fact that the carbon, if the temperature is not too high, contains some hydrogen, so that the deposit is in the form of a sticky but hard tar. The gas leaves the centre cracking zone at a high temperature, which is lowered by the absorption of some of its heat by the brickwork in the lower part 22 of the checkerwork, which had been cooled by the incoming cold air in the previous combustion cycle. The partially cooled gas leaves the checkerwork through the pipe 16.

These cycles are then alternately repeated. To secure a continuous supply of hot cracked gas, two checkerworks can be used, each delivering cracked gas while the carbon is being burned out of the other one, or the cracked gas can be stored in a gase holder from which gas can be supplied through a pipe 26 during the interval when the carbon is being burned out of the checkerwork. The gas holder may be of any suitable form such as the inverted bell 24 water sealed in a tank 25.

With some natural gases, the amount of carbon deposited is so large that more heat would be developed than can be absorbed if all this carbon were burned to carbon dioxide. Under these conditions, the supply of air can be limited and part of the carbon burned to carbon monoxide with the production of less heat, yet with the complete removal of the carbon, due to the high temperature of the combustion and the consequent displacement of the condition of chemical equilibrium toward the production of carbon monoxide.

Gas or vapors produced from coal, oil or other materials may be cracked in the same way.

This invention can also be used for cracking the vapors or heavy oils into the vapors of lighter oils. All such cracking means the reduction of the percentage of carbon in the vapor, and in this invention this rejected carbon is deposited on the hot checkerwork and by its combustion furnishes the required heat for the operation. Where such heavy oils have a temperature of vaporization at normal pressure that is above their decomposition temperature, they may be evaporated at lower pressures into a large volume of gas high in hydrogen and such suspended vapor may be cracked in accordance with this invention. In such case the ratio of carbon to hydrogen will not only be lowered by the decomposition of some of the accompanying carbon but, under the unstable condition in the oil molecule pro-

duced by the high temperature, some of the surrounding hydrogen will also be absorbed, further lowering the ratio of carbon to hydrogen in the molecule and correspondingly lowering the boiling temperature of the original oil vapor.

Having thus described my invention, what I claim is:—

1. A process of making hydrogen by decomposing hydrocarbon gas, which comprises passing the gas in contact with refractory material of increasing temperature with exclusion of air, the maximum temperature of said material being above the decomposing temperature of said gas, and then of decreasing temperature, the decomposition being accompanied by deposition of carbon near the material of maximum temperature, subsequently burning said deposited carbon with heated air to re-heat said material, and absorbing part of the heat of the products of said combustion in the part of said material with which said gas initially came in contact.

2. A process of making hydrogen by decomposing hydrocarbon vapors which comprises passing the vapors in contact with refractory material of gradually increasing temperature until the temperature of said material is above the decomposition temperature of said vapor with exclusion of air with deposition upon said material of maximum temperature of the carbon resulting from the decomposition of said vapor, and then bringing the gaseous products of said decomposition in contact with said material of gradually decreasing temperature; subsequently re-heating said material at the point of maximum temperature by burning said deposited carbon with a current of air, passing through said material in a direction contrary to the direction of passage of said vapor.

3. A process of making products of high hydrogen percentage content from hydrocarbon gas or vapour having hydrogen percentage content lower than that of the desired products, which comprises passing the same through a refractory checkerwork highly heated in its intermediate portion and cooler toward the ends with heating of the gas in the first portion of the checkerwork encountered by the gas or vapour, cracking of the gas or vapour in said intermediate hot portion of the checkerwork and deposit of carbon therein, and heating of the last portion of the checkerwork encountered by the hot cracked gas, and when the temperature of the intermediate portion of the checkerwork drops below an efficient gas or vapour cracking temperature stopping the gas flow and passing air through the checkerwork in the opposite direction to the gas or vapour with heating of the air in the first part of the checkerwork encountered by the air, combustion of the deposited carbon in the inter-

mediate portion of the checkerwork and re-heating of the intermediate portion and re-heating of the last portion of the checker-work encountered by the products of combustion.

- 5 4. A process of making products of high hydrogen percentage content from hydro-carbon gas or vapour having hydrogen percentage content lower than that of the de-sired products, which comprises passing the gas or vapour and air alternately and in opposite directions through a refractory checkerwork, heating the gas or vapour to cracking temperature with heat left by egress of products of combustion in the portion of the checkerwork first encountered by the gas or vapour, cracking the gas or vapour in an intermediate portion of the checkerwork by heat remaining in said portion from burning
- 10 carbon deposited by a previous cracking operation, heating the portion of the checkerwork last encountered by the cracked gas with heat carried by the gas out of the cracking zone, heating air with the heat left in the checker-work first encountered by the air from emerging cracked gas, burning carbon de-posed in an intermediate portion of the checkerwork by the previous cracking operation with said heated air thereby reheating the checkerwork to cracking temperature, and reheating the portion of checkerwork first encountered by the gas or vapour with the heat of the products of carbon combustion.
- 15 5. A process of making hydrogen by de-composing hydrocarbon gas, which comprises progressively heating the gas to a tempera-ture above its decomposition temperature and then progressively cooling the gas, the heating and cooling being effected by passing the
- 20 gas in contact with a mass of refractory ma-terial heated to temperatures progressively higher and then progressively lower along the path of the gas.
- 25 6. A process according to claim 5, in which the maximum temperature of the gas is ap-proximately 1500° F.
- 30 7. A process according to claim 5, in which the maximum temperature of the refractory material is approximately 1800° F.

50 In witness whereof, I have hereunto set my hand.

FREDERICK T. SNYDER.
